ATTORNEY

UNITED STATES PATENT OFFICE.

WILLIAM KEMERY, OF MASSILLON, OHIO.

PORTABLE FENCE.

SPECIFICATION forming part of Letters Patent No. 321,978, dated July 14, 1885.

Application filed February 24, 1885. (No model.)

To all whom it may concern:

Be it known that I, WILLIAM KEMERY, a citizen of the United States, residing at Massillon, in the county of Stark and State of Ohio, 5 have invented certain new and useful Improvements in Portable Fences, and I do hereby declare that the following is a full, clear, and exact description of the same, reference being had to the annexed drawings, making a part 10 of this specification, and to the letters and figures of reference marked thereon, in which—

Figure 1 is a side elevation showing a fence on level ground. Fig. 2 is a side view of the locking and supporting devices, showing transverse view of fence. Fig. 3 is a side view of the locking and supporting devices and transverse view of the fence, showing the fence on a hillside. Fig. 4 is a side elevation showing the fence placed on uneven ground. Fig. 15 5 is a side view of the locking and supporting devices for detachable panels, showing the parts in proper position to lock the panels. Fig. 6 is a side view of the locking and supporting devices, showing the locking-lever 20 locked to the side of the brace. Fig. 7 is a side view of the locking and supporting devices, showing the locking-lever locked to the under edge of the brace. Fig. 8 is a side view 25 of locking and supporting devices for permanent panels, showing the panels removed.

The present invention has relation to portable fences, which are designed to be easily constructed and adjusted, and which at the same time will be cheap and well adapted for 30 the purpose designed; and the invention consists in the different parts and combination of parts hereinafter described, and particularly pointed out in the claims.

Similar letters of reference indicate corresponding parts in all the figures of the drawings.

In the accompanying drawings, A represents a panel of the fence, which is composed of the horizontal bars or boards a, the perpendicular bars or boards a', and the wires b, and 45 may be made of any desired length, said bars or boards a and a' being securely held together by suitable clamping-bolts, B, one bolt being used in a place, so that the panel A can be easily changed so as to have the bars or 50 boards a' assume a perpendicular position when the fence is placed on an incline, as seen

in Fig. 4, and at the same time fit closely to the ground:

The base or sill C is substantially of the form shown in the drawings, and is placed under 55 the panels A, as shown in the drawings. This base or sill C is provided with the shoulder c, and is for the purpose of holding the panels A in proper position, together with the wire D. The wire D is securely attached to the base or 60 sill C, as seen in the drawings. The opposite end of the wire D is attached to the brace E, as shown in Figs. 1, 2, 3, 4, and 8, when permanent panels are used, and to the locking-lever F, as shown in Figs. 5, 6, and 7, when 65 detachable panels are used. The object of providing detachable panels is to provide a convenient passage-way through the fence proper. The brace E is substantially of the form shown in Figs. 1, 2, 3, 4, and 8, and is 70 attached to the base or sill C, as shown in the drawings, by means of the clamping-bolt d. The brace E is provided with slot G, which is for the purpose of properly adjusting the fence on a steep hillside, the holes H being 75 used when the hillside is less steep. The top or upper end of the brace E is rounded, as shown in the drawings, so that said brace can be easily forced down, and at the same time the wire D will securely bind the panels A 80 together. When detachable panels are placed in the fence for the purpose of forming a passage-way, the brace E is formed as shown in Figs. 5, 6, and 7, and the locking-lever F attached to said brace, as shown in said 85 figures.

In case it is desired to place detachable panels in the fence on a hillside, they are properly adjusted perpendicularly by means of the notches or recesses h, the locking-lever F being adjusted by means of holes h'. Said locking-lever F is held in the desired position by means of the pin I. Said pin I may be placed in the position shown in Fig. 6, or as shown in Fig. 7.

Having now fully described my invention, what I claim as new, and desired to secure by Letters of Patent, is—

1. In a portable fence, the combination, with the base or sill C, provided with the shoulder 90 c, of the wire D, attached at one end to the said base or sill C, the movable brace E, to

which the other end of the wire is attached, and means for securing said brace to the sill, substantially as and for the purpose specified.

2. In a portable fence, the combination of 5 the brace E, rounded at its top or upper end, the sill C, the wire D, attached to said brace E and to the sill C, and means for securing the brace, substantially as and for the purpose specified.

In testimony that I claim the above I have to hereunto subscribed my name in the presence of two witnesses.

WILLIAM KEMERY.
